WITNESS:

*Louisa Pingry,
INVENTOR*
BY *Victor J. Evans*
ATTORNEY

UNITED STATES PATENT OFFICE.

LOUISA JANE PINGRY, OF TULSA, OKLAHOMA.

MATTRESS PROTECTOR.

Application filed September 30, 1925. Serial No. 59,629.

This invention relates to improvements in mattress protectors, the general object being the suspending of a length of fabric upon a bed spring in order that the lower side of the mattress when arranged upon a bed will be spaced from the spring in eliminating the possibility of the mattress being torn upon the spring and side edges of sheets when tucked under the mattress.

Another object of my invention resides in the provision of the cover *per se* and having fitted thereto a plurality of attaching clips secured within the binding therefor whereby the spring frames may be engaged by the clips to support the protector thereupon.

With the above and other objects in view, the invention further includes the following novel features and details of construction, to be hereinafter more fully described, illustrated in the accompanying drawing and pointed out in the appended claim.

In the drawing:—

Figure 1 is an elevation of my invention as applied.

Figure 2 is a sectional view taken on line 2—2 of Figure 1, illustrating the construction of the cover and the manner in which the latter is attached to the spring frame.

Referring to the drawing in detail, wherein like characters of reference denote corresponding parts, the reference character 10 indicates an endless bar forming the frame of a bed spring, not shown, being of the usual and well known construction and forming no part of the present application for Letters Patent but being merely shown for purposes of illustration in bringing forward the novel advantages of the above entitled invention.

The invention resides in the provision of a protector, as indicated at 11, having outer or bottom and top layers of bed ticking as indicated at 12 and an intermediate layer

of oil cloth 13, all of which having registering ventilating openings 14 therein and a binding strip secured in the usual manner to the edges thereof. Lengths of wire, as indicated at 16, have their upper end portions 17 intersecting as at 18 and fitted and secured beneath the binding strip 15 upon the upper side of the protector 11. The remaining portion of each length of wire being bent intermediately upon itself to provide a resilient looped portion 19 adapted to extend around and beneath the frame 10 to support the cover 12 thereupon.

It is to be noted that a plurality of these fastening means are secured to the opposite sides and ends of the protector 12 in securing the latter to the frame 10 and in providing the resilient support for the mattress, not shown, irrespective of the springs, not shown, fitted within the frame 10.

The invention is susceptible of various changes in its form, proportions and minor details of construction, and the right is herein reserved to make such changes as properly fall within the scope of the appended claim.

Having thus described my invention what is claimed is:—

A mattress protector comprising a cover adapted to overlie a spring frame, a binding on the edge of the cover having portions overlapping the margins of the cover and attached thereto at spaced points, resilient clips having the upper ends thereof disposed to intersect one another and extended beneath said overlapping portions, and resilient loop portions projected from the intersecting portions of the clip being disposed for engagement with the under sides of the spring frame to yieldingly support the protector in position for use upon the frame and to insulate a mattress therefrom.

In testimony whereof I affix my signature.
LOUISA JANE PINGRY.
